PRODUCTION OF HIGH ANTIKNOCK GASOLINE

Filed Sept. 29, 1937

UNITED STATES PATENT OFFICE

2,220,699

PRODUCTION OF HIGH ANTIKNOCK
GASOLINE

Charles H. Angell, Chicago, Ill., assignor to Universal Oil Products Company, Chicago, Ill., a corporation of Delaware

Application September 29, 1937, Serial No. 166,271

4 Claims. (Cl. 196—9)

This is a continuation-in-part of my co-pending application Serial No. 151,136, which was filed on June 30, 1937, and which, in turn, is a continuation-in-part of my co-pending application Serial No. 661,242 filed on March 17, 1933, now Patent No. 2,128,897.

The invention relates to an improved process for the pyrolytic conversion of light hydrocarbon oil distillates, such as gasoline, naphtha and the like, of inferior motor fuel characteristics, particularly with respect to antiknock value, for the purpose of producing therefrom high yields of good antiknock gasoline. This type of cracking operation is now generally known in the art as "reforming" and will be hereinafter referred to as such.

The process of the invention involves two cooperative but independently controlled reforming steps, the first of which is devoted to treatment of the gasoline or other light distillate charging stock, while the second reforming step is devoted to treatment of selected high-boiling gasoline fractions resulting from the first reforming operation; said high-boiling gasoline fractions being first separated from the lower boiling gasoline fractions of the first reforming operation, thence utilized as absorber oil for recovering readily polymerizable olefins such as propene and/or butenes from the process gases and then subjected to further treatment in the second mentioned reforming step in commingled state with the absorbed polymerizable gases; a full boiling range gasoline of high antiknock value being recovered from the last mentioned reforming operation and including twice reformed gasoline and gasoline polymers resulting from the simultaneous treatment of said polymerizable gases and heavy gasoline fractions.

The invention is particularly well adapted to the treatment of light distillates of unusually high paraffinic nature which cannot be readily reformed to produce high yields of good antiknock gasoline in a single cracking operation. Gasoline or naphtha recovered from Muskegon crude, as well as some Pennsylvania distillates, exemplify this type of charging stock. On the other hand, as applied to the treatment of other light distillates of a less paraffinic nature, the process permits the production of gasoline of unusually high antiknock characteristics. Each of these particular adaptabilities of the process herein provided results from the combination of two important features of the invention. One of these features resides in the provision for separating the gasoline produced in the first reforming step

of the system into selected low-boiling fractions of satisfactory antiknock value and higher boiling fractions of inferior antiknock value and subjecting the latter to further reforming in a second reforming step of the system. The other of the two important cooperative features resides in the provision for utilizing the poor antiknock high-boiling gasoline fractions recovered from the first reforming step as an absorption medium for normally gaseous products of the process, whereby to recover from the latter readily polymerizable olefins gases such as propene and/or butenes, and supplying resulting enriched absorber oil to the second reforming step wherein the heavy gasoline fractions and absorbed gases are subjected to simultaneous treatment under conditions which result in the production of a full boiling range gasoline of high antiknock value.

The invention also includes other advantageous features which, in the cooperative combinations provided, are believed to involve invention over the prior art. These features will be explained in conjunction with the subsequent description of the accompanying drawing.

The drawing, which is diagrammatic, illustrates one specific form of apparatus embodying the features of the invention and in which the process herein provided may be conducted.

Referring to the drawing; the charging stock, which may be any desired light distillate (either straight-run or cracked, or a mixture of straight-run and cracked products) containing at least a substantial quantity of gasoline or gasoline fractions of poor antiknock value, is supplied through line 1 and valve 2 to pump 3 by means of which it is fed through line 4 and valve 5 to heating coil 6. The charging stock may, when desired, be preheated in any well known manner, not illustrated, prior to its introduction into heating coil 6.

A furnace 7, of any suitable well known form, provides the required heat to the charging stock passing through heating coil 6 to bring the same to the desired high cracking temperature, preferably at a substantial superatmospheric pressure, and preferably heating coil 6 and furnace 7 are of such well known form that the oil is maintained at a high cracking temperature for a considerable predetermined time in the heating coil.

The highly heated products are discharged from heating coil 6 through line 8 and are preferably cooled sufficiently as they pass through this line to prevent their excessive further cracking. The cooling is preferably accomplished at least in part by a substantial reduction in the

- pressure imposed on the stream of heated products as they pass through valve 9 in line 8 and additional cooling may be accomplished by the introduction of a suitable cooling oil into line 8, in the manner to be later described, and/or by indirect heat exchange between the relatively hot products and a suitable cooling medium. Means for accomplishing cooling by the latter method is not illustrated but is now well known in the art.
- 10 The partially cooled products from heating coil 6 are introduced into chamber 10 wherein their vaporous components are separated from heavy non-vaporous products such as residual liquid and heavy polymers. The non-vaporous residue 15 is withdrawn from the lower portion of chamber 10 through line 11 and valve 12 to cooling and storage or elsewhere, as desired, while the vaporous products are supplied from chamber 10 to fractionation in fractionator 13.
- 15 Chamber 10 and fractionator 13 are, in the particular case here illustrated, the lower and upper portions, respectively, of column 14, the two zones being separated by suitable partition or tray 15 through which vaporous products pass 20 from chamber 10 to fractionator 13 and upon which reflux condensate formed in fractionator 13 may collect.
- 20 Chamber 10 and fractionator 13 are, in the particular case here illustrated, the lower and upper portions, respectively, of column 14, the two zones being separated by suitable partition or tray 15 through which vaporous products pass 25 from chamber 10 to fractionator 13 and upon which reflux condensate formed in fractionator 13 may collect.
- 25 Fractionated vapors of the desired end-boiling point, which preferably include substantially all 30 of the components of the vapors supplied to fractionator 13 boiling within the range of gasoline and which may, when desired, also include somewhat higher boiling materials such as heavy naphtha fractions, kerosene, kerosene distillate 35 and the like, are removed, together with normally gaseous products of the reforming operation, from the upper portion of fractionator 13 and directed while still in hot vaporous state through line 16 and valve 17 to further fractionation in fractionator 18.
- 30 The purpose of fractionator 18 is to condense and separate from the vaporous products supplied thereto substantially all of their components except the normally gaseous products 35 and selected light gasoline fractions which are of satisfactory antiknock value. The condensed high-boiling components, which include or consist of high-boiling gasoline fractions of unsatisfactory antiknock value, are removed from the 40 lower portion of fractionator 18 through line 19 and valve 20 to pump 21 by means of which they are directed to further treatment, as will be later described. The normally gaseous products 45 and desirable light gasoline fractions are directed from the upper portion of fractionator 18 through line 22 and valve 23 to condensation and cooling in condenser 24, wherefrom the resulting distillate and uncondensed gases pass through line 25 and valve 26 to collection and separation in 50 receiver 27. The uncondensed gases may be released from receiver 27 through line 28 and valve 29 to storage or elsewhere, as desired, or they 55 may be supplied, all or in part, by well known means, not illustrated, to absorber 55. Distillate collected in receiver 27 is removed therefrom through line 30 and may be withdrawn, all or in part, from the system to storage or to any desired further treatment through valve 31 in line 30.
- 60 Ordinarily, however, the distillate collected in receiver 27 will contain a substantial quantity of dissolved normally gaseous products and the temperature and pressure conditions employed in receiver 27 may be so controlled that substantially all, or at least a major portion, of the

readily polymerizable high-boiling gases such as propene and butenes, as well as the corresponding saturated compounds, remain dissolved in the distillate. In such cases, the distillate is preferably stabilized to reduce its vapor pressure to the desired degree by liberating dissolved gases therefrom and the gases released from the distillate by said stabilization are supplied to absorber 55. In other cases, temperature and pressure conditions may be so controlled in receiver 27 that a substantial quantity or a major portion of the high-boiling gases are separated from the distillate in this zone, in which event gaseous products from receiver 27 are supplied to absorber 55 and stabilization of the distillate 15 may sometimes be dispensed with. The first described mode of operation is the one most commonly employed and is the one here illustrated and described in more detail in conjunction with the drawing.

20 The distillate to be stabilized, which consists of light gasoline fractions and dissolved gases, is directed from receiver 27 through line 32 and valve 33 to pump 34 wherefrom it is fed through line 35 and valve 36 to stabilizer 40, preferably 25 first passing through heat exchanger 37 wherein it is reheated sufficiently to effect its appreciable vaporization by indirect heat exchange with a suitable heating medium from within the system or from an external source, the heated distillate 30 being directed from heat exchanger 37 through line 38 and valve 39 into stabilizer 40.

25 Stabilizer 40 may comprise any desired type of stabilizing equipment and, in the case here illustrated, employs heating or reboiling means in the 35 lower portion thereof, such as closed coil 41 through which a suitable heating medium is circulated, and also employs cooling means in the upper portion of the stabilizer, such as closed coil 42 through which a suitable cooling medium 40 is circulated by means of lines 43 and 45 controlled, respectively, by valves 44 and 46. Any other well known means for establishing the desired equilibrium conditions may, however, be employed in stabilizer 40, including means for 45 introducing suitable cooling and/or heating media directly into the stabilizer. The stabilization in stabilizer 40 is preferably controlled to liberate substantially all of the C₄ and lighter dissolved gases and thereby leave a distillate of 50 unusually low vapor pressure.

55 The stabilized distillate is withdrawn from the lower portion of stabilizer 40 through line 47 and may be directed through valve 48 to cooling and storage or to any desired further treatment 55 or, when desired, regulated quantities of this material may be utilized as a heating medium in heat exchanger 37, to which the material is supplied from line 47 through line 49 and valve 50 and wherefrom it may be directed through line 60 51 and valve 52 back into line 47.

65 The gaseous products liberated from the distillate in stabilizer 40 are directed from the upper portion thereof through line 53 and valve 54 to absorber 55 wherein their desirable high-boiling components, including substantially all of the propene and butene fractions, are recovered from the low-boiling gases by absorption. In accordance with the provisions of the invention, the material employed as the absorption 70 medium in absorber 55 comprises regulated quantities of the selected high-boiling fractions recovered, as previously described, from fractionator 18. This material is directed from pump 21 through line 56 and valve 57 to the upper por- 75

tion of absorber 55, but is preferably first cooled to a relatively low temperature, prior to its introduction into the absorber. Partial cooling of a portion or all of the condensate from fractionator 18 may be accomplished by passing the same in indirect heat exchange with the distillate in stabilizer 40 whereby to reheat and reboil the latter. This is accomplished, in the case here illustrated, by diverting regulated quantities of the condensate from line 56 through line 58, valve 59, closed coil 41, line 60 and valve 61 back into line 56. Additional cooling of the absorber oil may be accomplished in cooler 62 through which all or a regulated portion of the condensate from line 56 is passed by means of lines 63 and 65 controlled, respectively, by valves 64 and 66, valve 67 in line 56 being either closed or only partially open, as desired.

The relatively low-boiling gases, which remain unabsorbed in absorber 55, are released from the upper portion of this zone through line 68 and valve 69. The enriched absorber oil, which preferably contains substantially all of the readily polymerizable olefins contained in the gaseous products supplied to absorber 55, is directed from the lower portion of the latter zone through line 70 and valve 71 to pump 72 by means of which it is fed through line 73 and valve 74 to further cracking in heating coil 75.

When all of the condensate from fractionator 18 is not required as absorber oil that portion not supplied to absorber 55 may be supplied directly to heating coil 75 by diverting the same from line 56 through line 76 and valve 77 into line 73.

Heating coil 75 is located within a suitable furnace 78 and, preferably, heating coil 75 and furnace 78, like heating coil 6 and furnace 7, are of such well known form that the oil passing therethrough is maintained therein at a high cracking temperature for a substantial predetermined time. The conditions of temperature, pressure and time employed in heating coil 75 are regulated to effect a material improvement in the antiknock value of the high-boiling gasoline fractions supplied thereto from fractionator 18, as well as to effect conversion of any higher boiling fractions of the condensate supplied to this zone for the production of high yields of good antiknock gasoline therefrom and also to effect polymerization of the olefinic gases recovered in absorber 55 and supplied to heating coil 75.

The hot conversion products are discharged from heating coil 75 through line 79 and are introduced through valve 80 in this line into separating chamber 81, preferably after being cooled sufficiently as they pass through line 79 to prevent any excessive continued cracking. This cooling, as in the case of the heated products discharged from heating coil 6, is preferably accomplished, at least in part, by a substantial reduction in the pressure imposed upon the stream of heated products as they pass through valve 80 in line 79 and any required additional cooling may be accomplished by the introduction of a suitable cooling oil into line 79, in the manner to be later described, and/or by indirect heat exchange in any well known manner, not illustrated, between the relatively hot conversion products and a suitable cooling medium, which latter may be any suitable relatively cool oil from within the system or from an external source.

Separation of high-boiling polymers and other heavy liquids of a residual nature from vaporous

and gaseous products is accomplished in chamber 81, the residual liquid being removed from the lower portion of this zone through line 82 and valve 83 to cooling and storage or elsewhere, as desired, while the vaporous products are directed, in the case here illustrated, from chamber 81 through a suitable partition or the like 84 into fractionator 85 which, in this particular case, comprises the upper portion of separating and fractionating column 82, the lower portion of which comprises chamber 81.

The components of the vaporous products supplied to fractionator 85 which boil above the range of the desired gasoline product are condensed in this zone as reflux condensate and, in accordance with one specific mode of operation herein provided, a full boiling range gasoline having an end-point of the order of 350 to 400° F. or more, for example, is removed together with the normally gaseous products of this stage of the system from the upper portion of fractionator 85 in vaporous state and directed through line 86 and valve 87 to condensation and cooling in condenser 88. The resultant distillate and uncondensed gases are directed through line 89 and valve 90 to collection and separation in receiver 91. The uncondensed gases are released from the receiver through line 92 and valve 93 and may, when desired, be directed by well known means, not illustrated, to absorber 55. Distillate collected in receiver 91 may be directed therefrom through line 94 and valve 95 to storage or to any desired further treatment or this material may be subjected to stabilization in stabilizer 40 or in a separate stabilizer, as desired.

When it is desired to stabilize the distillate collected in receiver 91, it may be directed through line 96 and valve 97 to pump 98, by means of which it is fed through line 99 and may be directed either to stabilizer 40 or to stabilizer 100, preferably after being reheated and partially vaporized in any desired manner. Two means of reheating and partially vaporizing the distillate are illustrated in the drawing, one of which comprises heat exchanger 37, previously described, to which the distillate may be supplied from pump 98 through line 99, line 101, valve 102 and valve 103 and wherefrom it may be directed through line 38 and valve 39 into stabilizer 40. The other means illustrated comprises heat exchanger 104 to which the distillate is directed from pump 98 through line 99 and valve 105 passing through the heat exchanger in indirect heat exchange with all or a regulated portion of the condensate being supplied to heating coil 75, the latter being diverted in regulated quantities from line 73 through line 106, valve 107, heat exchanger 104 and thence through line 108 and valve 109 back into line 73, valve 110 in line 73 being regulated to suit requirements. When heat exchanger 104 is utilized, the reheated distillate is discharged from this zone through line 111 and valve 112 into line 101 wherefrom it may be supplied either through line 113 and valve 114 to stabilizer 40 or through line 115 and valve 116 to stabilizer 100.

In accordance with another specific mode of operation provided by the invention, fractionation may be so controlled in fractionator 85 as to remove only selected low-boiling gasoline fractions, together with normally gaseous products, as the overhead vaporous stream from this zone and to condense high-boiling gasoline fractions in the upper portion of fractionator 85. In such cases, the light gasoline fractions are condensed and re-

covered in receiver 91 wherein they are separated from uncondensed gases and may be either removed from the system to storage or further treatment, or supplied from receiver 91, in the 5 manners previously explained, to stabilization in either stabilizer 40 or stabilizer 100, as desired.

The last described method of operation is particularly desirable in case it is advantageous to 10 separately treat the low-boiling and high-boiling 15 gasoline components of the vaporous products supplied to fractionator 85, or in case either the low-boiling or the high-boiling gasoline fraction requires further treatment and the other fraction does not. In accordance with this method of 20 operation, the high-boiling gasoline fractions are removed as a side-stream from a suitable intermediate point in fractionator 85, provision being made, in the case here illustrated, for removing the same from this zone through line 117 and valve 25 118 wherefrom they may be directed to cooling and storage or to any desired further treatment or may be first reboiled in any well known manner, not illustrated, to substantially free the same of dissolved gases and low-boiling components 30 within the range of the desired overhead product from fractionator 85.

It is also within the scope of the invention, instead of removing the high-boiling gasoline fractions as a side-stream from fractionator 85, to 35 employ a separate secondary fractionator (similar to fractionator 18) to which the full boiling range gasoline and uncondensed gases may be directed in vaporous state from the upper portion of fractionator 85 and wherefrom low-boiling and 40 high-boiling gasoline fractions of the desired characteristics are separately recovered in the manner previously described in connection with fractionator 18.

The reflux condensate formed in fractionator 45 85 which boils above the range of the desired final gasoline product of this stage of the system, is directed from the lower portion of this zone through line 119 and valve 120 to pump 121 and is preferably employed as a heating and/or cooling 50 medium within the system. This material may be utilized, all or in part, for example, as a means of preheating the gas-containing condensate supplied to heating coil 75 by passing the same in indirect heat exchange therewith in heat 55 exchanger 124, to which condensate from fractionator 85 is directed by means of line 122 and valve 123 and through which all or a regulated portion of the gas containing condensate being supplied to coil 75 is directed by means of line 129 60 in line 125, valve 126, line 127 and valve 128, valve 129 in line 13 being regulated to suit requirements. The partially cooled reflux condensate from fractionator 85 is directed from heat exchanger 124 through line 130 and valve 131 into line 132. 65 When heat exchanger 124 is not utilized or when only a portion of the reflux condensate from the lower portion of fractionator 85 is supplied to this zone, all or the remaining portion of this reflux condensate may be supplied to line 132 through line 133 and valve 134. Reflux condensate may be removed from line 132 and from the system to 70 cooling and storage or elsewhere, as desired, by means of line 135 and valve 136. Preferably, however, a portion or all of this material is utilized as cooling oil in line 8 from heating coil 6 and/or in line 19 from heating coil 75. This may be accomplished by directing regulated quantities of the condensate through valve 137 in line 132 and through one or more branch lines 138 controlled 75 by valve 139 into line 8 on either or both

sides of valve 8 and/or by directing the reflux condensate in regulated quantities from line 132 through line 140 and through one or more branch lines 141 controlled by valves 142 into line 79 on either or both sides of valve 80.

The reflux condensate formed in fractionator 13 may also be utilized in regulated quantities as a cooling medium and/or as a heating medium within the system. This material is withdrawn from the lower portion of fractionator 13 through line 144 and valve 145 to pump 146 wherefrom it is preferably directed, all or in part, through line 147 and valve 148 into and through closed coil 149 disposed within the lower portion of fractionator 18, wherein it serves as a heating 15 medium for reboiling the condensate formed in this zone and wherefrom it is discharged through line 150. It may thence be directed in regulated quantities through line 132 into line 8, in the manner previously described, to serve as a cooling 20 medium, and/or through line 140 into line 79, in the manner previously described, wherein it also serves as a cooling medium. Regulated quantities of the reflux condensate formed in fractionator 13, may, when desired, be removed 25 from the system to cooling and storage or elsewhere, as desired, by means of line 151 and valve 152 communicating with line 147 or in any other well known manner, not illustrated.

Stabilizer 100, when utilized, is preferably provided with suitable reboiling means in the lower portion thereof, such as closed coil 155 through which any suitable heating medium may be circulated by means of lines 156 and 158 controlled, respectively, by valves 157 and 159. Stabilizer 35 100 is also preferably provided with means for cooling in the upper portion thereof, such as, for example, closed coil 160 through which any suitable cooling medium may be circulated by means of lines 161 and 163 controlled, respectively, by valves 162 and 164. The gases liberated from the distillate in stabilizer 100 are removed from the upper portion of this zone through line 165 and valve 166 and may, when desired, be directed by well known means, not illustrated, to absorber 55. The stabilized distillate is withdrawn from the lower portion of stabilizer 100 through line 167 and valve 168 to cooling and storage or to any desired further treatment. The stabilization in stabilizer 100 is preferably controlled to leave a major portion, at least, of the C₄ hydrocarbons in the stabilized distillate so that the latter will be of sufficiently high vapor pressure that, when blended with the stabilized distillate from stabilizer 40, there will be formed a blend having a vapor pressure (Reid) of the order of 8 to 12 lbs. per sq. in.

The preferred range of operating conditions which may be employed to accomplish the objects of the invention in an apparatus such as illustrated and above described, may be approximately as follows:

Heating coil 6 preferably employs an outlet temperature within the range of 900 to 1050° F., or thereabouts, preferably with a superatmospheric pressure at this point in the system of from 200 to 1,000 pounds, or thereabouts, per square inch.

Separating chamber 10 is preferably operated at a substantially reduced pressure relative to 70 that employed at the outlet of heating coil 6, the reduced pressure ranging, for example, from a pressure within 50 pounds, or thereabouts, of that employed at the outlet of heating coil 6 down to substantially atmospheric pressure.

Fractionator 13 is preferably operated at substantially the same pressure as that employed in chamber 10, while fractionator 18 may be operated at substantially the same or reduced pressure.

Any desired pressure ranging from 300 pounds, or more, per square inch, superatmospheric, down to substantially atmospheric pressure may be employed in stabilizer 40 and any desired pressure within this range may also be utilized in stabilizer 100 when the latter zone is employed. Substantially the same or somewhat lower pressure relative to that employed in stabilizer 40 may be utilized in absorber 55.

15. The temperature and pressure conditions employed at the outlet of heating coil 75 may vary within substantially the same limits as those above mentioned in connection with heating coil 6. Ordinarily, however, the temperature and 20 pressure conditions in the two heating coils are not identical, either coil being operated under more severe cracking conditions than the other and the relative conditions in the two coils being regulated to suit requirements.

25. Chamber 81 is preferably operated at a substantially reduced pressure relative to that employed at the outlet of heating coil 75, which reduced pressure may range from 50 pounds, or thereabouts, below that employed at the outlet 30 of heating coil 75 down to substantially atmospheric.

35. Fractionator 85 is preferably operated at substantially the same pressure as that employed in chamber 81. The condensing and collecting portions of the system may utilize pressures substantially the same or somewhat lower than that employed in the preceding fractionating zone.

40. As an example of one specific operation of the process, conducted in accordance with the features of the invention in an apparatus such as illustrated and above described: The charging stock is a distillate from Muskegon, Michigan crude having a boiling range of approximately 100 to 550° F. and of exceptionally poor anti-knock value. This material is heated in coil 6 to an outlet temperature of approximately 950° F. at a superatmospheric pressure of about 800 pounds per square inch, as measured at the outlet of the heating coil. The resultant conversion 45 products are cooled to a temperature of approximately 670° F., prior to their introduction into chamber 10, which is operated at a superatmospheric pressure of about 100 pounds per square inch. Substantially the same pressure is employed in fractionator 13 from which an overhead vaporous stream having an end-boiling point of approximately 500° F. is supplied to fractionator 18. The latter zone is operated at a superatmospheric pressure of approximately 40 50 pounds per square inch and the overhead vaporous stream therefrom has an end-boiling point of approximately 300° F. Reflux condensate formed in fractionator 18 is reboiled by indirect heat exchange with reflux condensate from fractionator 13 as hereinafter described. A pressure approximately the same as that employed in fractionator 18 and a sufficiently low temperature is employed in receiver 27 so that at least the major portion of the normally gaseous products 55 of this stage of the system boiling above ethane remain dissolved in the distillate collected in this zone. In this particular operation, the distillate from receiver 27 is freed in stabilizer 40 of substantially all the butenes and lower boiling 60 gases, the same being supplied to absorber 55,

while the stabilized light gasoline fractions of low vapor pressure are recovered from stabilizer 40. The condensate formed in fractionator 18, which has an initial boiling point of approximately 275° F. and an end-boiling point of approximately 500° F. is cooled and supplied in regulated quantities to absorber 55 wherein it absorbs substantially all of the propenes and butenes from the gaseous products supplied to this zone. The resulting enriched absorber oil 10 and the remainder of the condensate from fractionator 18, not utilized as absorber oil, are supplied to heating coil 75 wherein the commingled materials are converted into high yields of good antiknock gasoline. A temperature of approximately 975° F. and a superatmospheric pressure of about 1000 pounds per square inch are employed at the outlet of heating coil 75, the resulting heated products being cooled to a temperature of approximately 675° F., prior to their 15 introduction into chamber 81. The latter zone is operated at a superatmospheric pressure of approximately 80 pounds per square inch and this pressure is substantially equalized in the succeeding fractionating, condensing and collecting 20 portions of the system. Reflux condensate formed in fractionator 85 is cooled and returned in regulated quantities to line 79 as a cooling medium. The overhead vaporous product from fractionator 85 has an end-boiling point of approximately 420° F. and the temperature and 25 pressure conditions in receiver 91 are so controlled as to leave substantially all of the butane and some of the lower boiling fractions dissolved in the distillate. The distillate from receiver 30 91 is stabilized in stabilizer 100 to a sufficiently high vapor pressure that, when commingled with the stabilized low vapor pressure light gasoline fractions from stabilizer 40, the vapor pressure of the final blended motor fuel product of the 35 process is approximately 8 to 10 pounds per square inch. In this operation, no substantial quantity of readily polymerizable olefins, such as propene and/or butenes, are contained in the gaseous products released from receiver 27, absorber 55, 40 receiver 91 and stabilizer 100. These relatively lean gases are therefore released from the system to storage or elsewhere, as desired.

The operation above described will yield per 50 barrel of straight-run distillate charged to the system, approximately 82% of full boiling range gasoline of the desired vapor pressure (8 to 10 pounds per square inch, or thereabouts). This product has an antiknock value equivalent to an 55 octane number of approximately 72 as determined by the motor method. The only other products of the process are a small yield of relatively heavy liquids and lean uncondensed gases.

I claim as my invention:

1. A conversion process which comprises subjecting hydrocarbon oil to cracking conditions of temperature and pressure in a conversion zone and fractionating the resultant vapors and gases to condense and separate fractions thereof heavier than gasoline, further fractionating the uncondensed gasoline-containing vapors and gases to form an intermediate condensate containing heavy gasoline fractions of inferior anti-knock value, a light gasoline condensate of satisfactory anti-knock value and a normally gaseous fraction, combining polymerizable components of said gaseous fraction with said intermediate condensate, subjecting the resultant mixture in a second conversion zone to independently controlled conditions of temperature and pressure 70 75 80 85 90 95 100

adequate to reform the intermediate condensate and polymerize normally gaseous olefins, and recovering from the resultant products a distillate boiling within the gasoline range.

5. 2. The process as defined in claim 1 further characterized in that said polymerizable components are combined with said intermediate condensate by scrubbing said gaseous fraction with at least a portion of the intermediate 10 condensate.

3. A conversion process which comprises subjecting hydrocarbon oil to cracking conditions of temperature and pressure in a conversion zone and fractionating the resultant vapors and gases 15 to condense and separate fractions thereof heavier than gasoline, further fractionating the uncondensed gasoline vapors and gases to separate therefrom a heavy gasoline condensate of inferior anti-knock value, subjecting the remaining light 20 gasoline vapors and gases to final condensation under sufficient pressure to liquify a substantial portion of the gases with the light gasoline vapors, removing from the resultant final con-

densate, by stabilization thereof, substantially all of the C₄ and lighter hydrocarbons contained therein, thereby forming a stabilized distillate of lower vapor pressure than commercial motor fuel, combining normally gaseous hydrocarbons 5 thus liberated from the final condensate with at least a portion of said heavy condensate, subjecting the resultant mixture in a second conversion zone to independently controlled conditions of temperature and pressure adequate to 10 reform the heavy condensate and polymerize normally gaseous olefins, separating from the resultant products a gasoline boiling condensate containing a substantial amount of C₄ hydrocarbons, and blending the last-named condensate 15 with said stabilized distillate to form a commercial motor fuel.

4. The process as defined in claim 3 further characterized in that said hydrocarbon oil is a light paraffinic distillate of the character of gasoline and naphtha. 20

CHARLES H. ANGELL.
